OTHER PUBLICATIONS

Photographs of "Imperial—Silver" model of pen manufactured by Sheaffer and conceded to publicly known as early as the late-1960s, as shown at <http://www.sheaffertarga.com/Imperial%20and%20Triumph/Sterling%20silver%20diamond%20pattern2.html>, downloaded Dec. 28, 2010 (3 pages).

Primary Examiner — Elizabeth Albert(74) *Attorney, Agent, or Firm* — Dicke, Billig & Czaja, PLLC(57) **CLAIM**

We claim the ornamental design for a writing instrument, as shown and described.

DESCRIPTION

FIG. 1 is a perspective view of a writing instrument showing our new design;

FIG. 2 is a front view of FIG. 1;

FIG. 3 is a back view of FIG. 1;

FIG. 4 is a left side view of FIG. 1, the right side view being a mirror image of the left side view.

FIG. 5 is an enlarged top view of FIG. 1; and,

FIG. 6 is an enlarged bottom view of FIG. 1.

Portions of the writing instrument shown in broken lines are for the purpose of showing features that form no part of the claimed design.

1 Claim, 4 Drawing Sheets(56)
